(57) CLAIM

The ornamental design for a cleaning product, as shown and described.

DESCRIPTION

FIG. 1 is a top front perspective view of a cleaning product, showing our new design;

FIG. 2 is a front elevation view thereof, the rear elevation view being a mirror image thereof;

FIG. 3 is a right elevation view thereof, the left elevation view being a mirror image thereof;

FIG. 4 is a top plan view thereof;

FIG. 5 is a bottom plan view thereof; and,

FIG. 6 is a top front perspective view of the cleaning product shown in use.

The evenly-sized broken lines showing a user's hand in FIG. 6 depict environmental subject matter that forms no part of the claimed design, while the remaining evenly-sized broken lines shown in the drawings depict portions of the cleaning product that form no part of the claimed design.

The unevenly-sized broken lines consisting of dash-dot-dash lines in the drawings depict the boundary of the claimed invention and it is understood that the claim extends to the boundary that forms no part of the claimed design.

The use of stippling indicates a contrasting appearance with the adjacent non-stippled portion surrounding the side openings.
